ATTORNEY

UNITED STATES PATENT OFFICE

RAY HOTTEL, OF DETROIT, MICHIGAN, ASSIGNOR TO CHRYSLER CORPORATION, OF DETROIT, MICHIGAN, A CORPORATION OF DELAWARE

VENTILATOR

Application filed March 30, 1929. Serial No. 351,336.

This invention relates to a ventilator and more particularly to a ventilator for use in a vehicle body.

When ventilators are used in the side of an automobile cowl, the means for operating the shutter of the ventilator usually consists of a lever projecting into the body. When it is desired to open the ventilator the lever is pushed by the foot and when the ventilator is closed the reverse movement is necessary. This has been found objectionable due to the fact that the operator scuffs his shoe when operating the lever for closing the ventilator. It is, therefore, an important object of this invention to provide a mechanism which opens and closes the ventilator by pushing on the operating lever.

Another object of the invention is to provide a tension means on the cover which holds the cover under tension in either opened or closed position.

A further object of the invention is to provide a ventilator having a frame, cover and operating means assembled as a unit to be placed adjacent an opening in the vehicle body.

Other objects and advantages of the invention will more fully appear from the following description and claims taken in connection with the accompanying drawing, in which:

Fig. 1 is a bottom view of the ventilator.

Fig. 2 is a sectional view on line 2—2 of Fig. 1 showing the cover in closed position.

Fig. 3 is a view corresponding to Fig. 2, but showing the cover in opened position.

Referring to the drawing wherein I have illustrated one particular embodiment of my invention, the reference numeral 10 designates a body panel such as the cowl of an automobile body and is provided with an opening 12, the periphery thereof being turned inwardly as at 14. The ventilator unit, which is received on the inner face of the panel 10, consists of a rectangular frame work 16 of Z section, a cover 18 pivotally supported on the Z section, and an operating mechanism.

On the inner surface of the panel 10 the usual trimming 20 has been shown and the

frame 16 fits in an opening 22 in the trimming, engaging the inner face of the panel 10. The Z frame 16 is provided with a flange 24 which rests against the inner face of the trimming 20. The portion 26 of the Z frame 55 closes the periphery of the opening 22 and a face plate 28, provided with an opening 30, engages the panel 10. The face plate is provided with a recess portion 32 to receive the inwardly turned flange 14 and a flange 34 60 extends into the opening 12. The flange 34 forms a seat for the cover 18 when it is in closed position.

A pair of supporting brackets 36 are secured to the face plate 28 which support a rod 38. Pivotedly supported on the rod 38 are two stampings 40, each having a rib 42 and a flange 44 which is secured to the cover 18, such as by spot welding. Secured to the portion 26 of the Z frame, opposite the brackets 36, is a U shaped stamping 46 which supports a rod 48. A cam 50 and a handle 52 are pivotally supported on the rod 48. Pivotally supported on the central portion of the U shaped member 46 I have provided a U shaped spring member 54 having its outer ends pivotally engaged in the rib 42. The U shaped member 54 is longer than the distance between its end supports and the arms of the member 54 are urged inwardly so that the ends of the spring are held under tension in the openings of the ribs 42. The cam 50 bears against both arms of the U shaped member at all times.

The adjacent ends of the cam 50 and handle 52 are notched as shown at 56 and a coiled spring 58 urges the handle toward the cam 50 with the notches of the handle 52 engaging the notches of the cam 50. The opposite ends of the spring 58 are bent outwardly, one 90 to engage an arm of the U shaped member 46, and the other to engage the outwardly extending portion of the handle 52, thereby urging the handle in one direction.

When the cover is closed the low portion 95 of the cam 50 is in engagement with the arms of the U shaped member 54 and when the operator pushes the handle in a direction as indicated by the arrow in Fig. 2, the notches of the handle, in engagement with the notches 100

of the cam 50, cause the cam to depress the lower portion of the arms 54 urging the cover outwardly as shown in Fig. 3. When the handle is released the spring 58 urges the handle back to its normal position leaving the cam 50 in a position as shown in Fig. 3. When it is desired to close the cover the handle is again pushed in the direction of the arrow and the cam is rotated back to 10 the position as shown in Fig. 2, the tension of the spring closing the cover.

A gasket 60 is provided on the under surface of the cover 18 to engage with the portion 34 of the Z shaped frame.

15 It will be understood that applicant has provided a ventilator which can be installed as a unit and that the operation of the device is simple. It will be noted that the same movement operates to either close or 20 open the cover and that the handle returns to its normal position after the cover has been opened or closed. The cover is held in either an opened or closed position by spring tension.

25 Various changes, including the size, shape and arrangement of parts, may be made without departing from the spirit of my invention and it is not my intention to limit the scope thereof other than by the terms of the 30 appended claims.

What I claim is:

1. In a ventilator, the combination of a frame member having a face plate provided with an opening and a perimetric flange at 35 right angles to said face plate, a cover for the opening in said face plate, a member for supporting said cover pivotally mounted on said frame and secured to said cover, a resilient element forming a connection between 40 said member and said frame, said member and said resilient element being within the boundary of the perimetric flange, and an operating handle projecting beyond the boundary of said perimetric flange.

45 2. In a ventilator, the combination of a frame having an opening therein, a cover for the opening, a connecting member having one end in operative connection with said cover and its opposite end connected to said 50 frame, a handle pivoted on said frame, and a cam member adapted to be rotated by said handle and having its face in contact with said connecting member.

55 3. In a ventilator, the combination of a frame having an opening therein, a cover for the opening, a connecting member having one end in operative connection with said cover and its opposite end connected to said frame, a handle pivoted on said frame, 60 a cam in axial alignment with said handle pivot rotatably supported adjacent thereto and having its face in contact with said connecting member, resilient means for urging said handle angularly and axially, and co- 65 operating means between said handle and

said cam for imparting a rotary movement to said cam by an oscillating movement of said handle.

4. In a ventilator, the combination of a frame, a cover swingingly supported on said frame, a rotary cam, a member movable by the rotation of said cam for pivoting said cover, a handle for rotating said cam, and means for returning said handle to its normal position after rotation of said cam. 75

5. In a ventilator, the combination of a support, a cover pivotally mounted on said support, a tension element between said cover and its support, a cam in engagement with said tension element, and means for rotating 80 said cam in only one direction.

6. In a ventilator, the combination of a frame formed from a single stamping, said frame comprising a face plate having an opening therein and a perimetric flange at 85 right angles to said face plate, a portion of said frame face plate being depressed and extending into the opening, a cover for the opening adapted to engage the depressed portion of said frame, and means for moving said cover, said means and said cover being carried by said frame. 90

7. In a ventilator, a frame having an opening therein, a door swingingly mounted on said frame, a resilient link pivotally mounted on said frame and pivotally connected with said door, said link being tensioned so as to normally hold said door in a closed position, and means bearing between the pivoted extremities of said link for rotating the same 100 about its pivotal connection with said frame and simultaneously augmenting its tension for closing said door when said means is released. 105

8. In a ventilator, a frame having an opening therein, a door swingingly mounted on said frame, a resilient link pivotally mounted on said frame and pivotally connected with said door adapted to independently urge said door in only one direction and toward a 110 closed position, a cam for swinging said link about its pivotal connection with said frame so as to open said door, operating mechanism for said cam comprising an oscillating handle, and a ratchet connecting said cam and handle for rotating said cam in a single direction by alternate oscillations of said handle. 115

9. In a ventilator, a frame having an opening therein, a door swingingly mounted on said frame, a resilient link pivotally mounted on said frame and pivotally connected with said door adapted to normally retain said door in a closed position, and means engageable with said link having a control lever operable in only one direction for both swing- 120 ing said link about its pivotal axis with said frame so as to open said door and for releasing said link so as to condition the latter 125 for closing said door. 130

10. In a ventilator, a frame having an opening therein, a door swingingly mounted on said frame, a resilient link pivotally mounted on said frame and pivotally connected with said door adapted to independently urge said door in only one direction and towards a closed position, and means engageable with said link having a control lever operable in only one direction for both swinging said link about its pivotal axis with said frame so as to open said door and for releasing said link ~~as~~ to condition the latter for closing said door.

RAY HOTTEL.
